United States Patent Office

Des. 221,120
Patented July 6, 1971

221,120

BICYCLE

Viktor Schreckengost, Cleveland Heights, Ohio, assignor to The Murray Ohio Manufacturing Co., Nashville, Tenn.

Filed Aug. 20, 1970, Ser. No. 24,613

Term of patent 14 years

Int. Cl. D12—11

U.S. Cl. D90—8

Fig. 3

FIG. 1 is a side elevational view of a bicycle showing my new design;

FIG. 2 is an elevational view of the side opposite that illustrated in FIG. 1;

FIG. 3 is a top plan view thereof;

FIG. 4 is a front perspective view thereof; and

FIG. 5 is a rear perspective view thereof.

The wheels are fragmentarily shown in FIGS. 1 and 2 for convenience of illustration only.

I claim:

The ornamental design for a bicycle, substantially as shown and described.
